LETTER OPENER

Theophilus Schmid, Jr., Chicago, and Andrew Benson, Wilmette, Ill.

Application February 17, 1936, Serial No. 64,370

3 Claims. (Cl. 120—35)

The invention relates generally to letter openers and more particularly to such openers adapted for manual operation to effect opening of the letter by cutting a narrow strip from the edge 5 of the envelope.

The primary object of the present invention is to provide a letter opener of this character embodying rotary cutting means and adapted for economical and rapid production and assembly.

10 Another object is to provide such an opener having an extremely small number of parts.

A further object is to provide such an opener having blunt edged cutting means whereby to 15 avoid danger to the user.

Another object is to provide a letter opener of this character wherein all the metal parts are 20 fully housed within a composition handle.

A further object is to provide a letter opener having two overlapping cutter elements, so constructed as to be fully housed and protected by 25 the handle and yet accessible for starting actuation by either a left or right handed user.

Other objects and advantages will become apparent from the following description, taken in 30 connection with the accompanying drawing, in which:

Figure 1 is a side elevation view showing a letter opener embodying the features of the invention.

35 Figure 2 is a right end view of the device shown in Figure 1.

Figure 3 is a top plan view of said device.

Figure 4 is a section view taken along the line 4—4 of Figure 1.

35 Figure 5 is an enlarged left end view of Figure 1.

Figures 6 and 7 are diagrammatic views of the two cutter assemblies showing the individual parts thereof.

40 For purposes of disclosure herein the invention is illustrated as embodied in a manually operable letter opener having an elongated body or handle 10 with a longitudinally extending guide slot 11 formed in one broad face thereof for passage of the edge of a letter longitudinally there-

45 through and provided with overlapping rotary cutters 13 and 14 mounted in the handle in such a position as to trim a narrow strip from an envelope in such movement.

50 As shown in Figures 2 and 3, the cutters 13 and 14 are mounted in the left hand end of the handle 10 in a slot 15 formed between a projecting upper bearing plate 16 and parallel projecting lower bearing plates 17 which define opposite 55 sides of guide slot 11 at said end of the handle.

In mounting the cutters 13 and 14, headed pins 18 are used, which pins project through parallel bores 19 in the bearing plates and are fixed in place by spinning out the recessed lower ends 18' of the pins. When thus mounted, the cutters are 5 rotatable on the pins 18 and their edges overlap as shown in Figures 3 and 5 so as to cut a narrow strip from the envelope as determined by the relation of the guide slot 11 to the abutting side faces of the cutters.

10 The handle 10 is preferably formed from a moldable material such as Bakelite, and is relatively narrow at its right end as shown in Figure 3, with a long flat rectangular facial area 20 on its upper side to receive advertising matter. In 15 its lower surface as shown in Figures 1, 3 and 4, the handle is preferably recessed as at 21 to avoid excessive weight and cost, it being noted that the guide slot is of full depth at points 11' and 11" so as to insure effective functioning of the 20 slot even though it is of reduced depth intermediate these points.

At its other or left end the handle 10 is relatively wide as shown in Figures 3 and 5 so that the bearing plates 16 and 17, which form part of 25 the handle, project beyond the extreme peripheral edges of the cutters 13 and 14. Moreover, the facial area 20 as shown in Figure 5 is elevated to substantially the height of the heads of the pins 18. Hence all of the metallic parts of the device 30 are guarded against causing undue damage to desk finishes and the like. Particularly, it should be noted that the metallic cutters 13 and 14 are housed by the bearing plates of the handle 10.

As a feature of advantage in the manufacture, 35 assembly and use of the device, the particular form, relationship and mounting of the cutters are of importance. Thus, the cutters in the present device are constructed to embody safe blunt cutting edges arranged to be held in operative 40 relation without the use of springs, and all of the parts are so formed as to permit manufacture thereof by means of relatively automatic machinery.

45 As shown in Figures 5 to 7, the cutters 13 and 14 are duplicates, and are formed by punching from saw steel. After the punching operation, in which a central hole 26 is formed, a large number of the cutter disks are clamped together on a long rod (not shown) and ground to provide an 50 accurately cylindrical outer face 21 (Figures 6 and 7). This operation may be performed on a conventional centerless grinder.

55 As a means for supporting the cutters 13 and 14 on the pins 18, bearing sleeves or members 29

and 30 are provided, and preferably these members 29 and 30 are provided with integral positioning flanges or disks 31 and 32 which are of substantially the same diameter as the cutters 5 and adapted to bear overlap and bear laterally against each other to produce proper lateral relationship of the two cutters 13 and 14. Thus the sleeve 29 (Figure 6) projects a substantial distance in each direction from its positioning 10 disk 31 and one projecting end 29' is of a reduced diameter so that it may project through the central hole 26 of the cutter with a press fit. In this assembly operation the cutter 14 is pressed firmly against the positioning disk 31 (Figure 5).
 15 On the sleeve 30, the integral positioning disk 32 is formed relatively close to one end as shown in Figure 7, and between the disk 32 and the other end of the sleeve 30 the sleeve is formed to provide for proper spacing and mounting of the 20 cutter 14. Thus this portion of the sleeve 30 has a reduced end 30' of a diameter arranged to project through the central hole 26 of the cutter 14 with a press fit. The reduced end 30' defines an abutment shoulder 30'' spaced from the disk an 25 axial distance equal substantially to the combined thickness of the cutter 13 and its positioning disk 31. Thus the disk 31 and its cutter 13 may run between the disk 32 and the cutter 14 to hold the two cutters in the desired lateral 30 relationship.

After the cutters have been pressed into position on their bearing sleeves, the two cutter units are ready for mounting in the handle 10, and this 35 operation is relatively simple. It will be noted that the sleeves 29 and 30 are of such a length as to provide a slight clearance between the ends of the sleeves and the bearing plates 16 and 17.

It will be noted that the edges of the disks 31 and 32, as well as the edges of the cutters 13 and 40 14 are blunt so that the user may contact any of these edges to impart a slight starting movement to one of the cutters. Such starting movement is usually effected by contacting the cutter at the point A (Figure 3), and it will be noted that 45 either cutter may be engaged for this purpose. Thus the device is capable of efficient use by either the right or left hand. In the preferred form shown the edges of both the disks 31 and 32 are knurled to facilitate such starting of either of 50 the cutters.

In the manufacture of the present letter opener the mounting or bearing sleeves 29 and 30 are made of such a length as to provide a slight 55 clearance between the ends of the sleeves and the bearing plates 16 and 17. The desired relationship of the two cutters is maintained by the projection of the parts 13 and 31 into the space between the parts 14 and 32 of the other assembly, 60 and sufficient clearance is provided between these

parts to permit the two cutter assemblies to rotate quite freely relative to each other.

As a practical matter the sleeves and their associated positioning disks are in the present case formed from brass which can be readily worked by conventional automatic screw machines. In such manufacture of the sleeve elements the dimensions may be held within close limits so as to insure proper working relationship between the parts after assembly, even though the assembly 10 operations are of a simple character. It has been found that the present opener operates without a manual starting operation when used upon envelopes of medium or relatively stiff grade and that a manual starting operation is required only 15 when the device is used on exceptionally heavy envelopes or upon crumpled or relatively thin envelopes.

We claim as our invention:

1. A letter opener having, in combination, a 20 handle, with a mounting slot therein, a pair of parallel pins extending across said slot, a pair of sleeves one mounted on each pin, a pair of circular cutters one mounted on each sleeve, said cutters being of such a diameter as to overlap and 25 abut laterally, a positioning disk formed integrally with one of said sleeves and extending parallel to the cutter in spaced relation thereto, the other cutter having its edge extending into the space between said disk and the spaced cutter in lateral 30 abutment with said spaced cutter, and a positioning disk formed integrally with the other sleeve and positioned to extend into said space in lateral abutment with the other positioning disk.

2. A letter opener comprising, in combination, a 35 body constituting a handle, said body having intersecting mounting and guide slots, a pair of parallel pins spanning said mounting slot on opposite sides of said guide slot, a pair of sleeves one rotatably mounted on each of said pins with 40 in said mounting slot, a pair of square edged cutters one mounted on each of said sleeves, said cutters being sized to overlap and abut laterally, and rigid means formed integrally with said sleeves operable to maintain said cutters in substantial lateral contact.

3. A letter opener having in combination a handle, having a mounting slot therein, a pair of parallel pins extending across said slot in spaced relation, a pair of sleeves, one mounted on each 50 of said pins, each of said sleeves having a positioning disk thereon arranged to overlap and run laterally against each other, a steel cutter mounted on one sleeve with one side in abutment with the disk of one of said sleeves and on the side 55 opposite from the other disk, and a steel cutter mounted on the other sleeve arranged to run laterally against the other side of said other cutter.

THEOPHILUS SCHMID, JR.

ANDREW BENSON,
